DOOR OPERATING MECHANISM FOR
TILTING FURNACESHarry L. McFeaters, New Castle, Pa., assignor to
Pennsylvania Engineering Works, a corpora-
tion of Pennsylvania

Application August 28, 1943, Serial No. 500,337

5 Claims. (Cl. 266—24)

This invention relates to tilting furnaces such as open hearth furnaces and more particularly to mechanism for operating the charging doors of such furnaces.

The charging doors of tilting open hearth furnaces while being opened and closed move vertically and an object of this invention is to produce improved mechanism for operating the doors of tilting open hearth furnaces.

Another object is to produce for use with a tilting furnace door operating mechanism employing a stationary hoisting unit, means for maintaining the tension in the hoisting line so nearly constant during tilting of the furnace that the furnace door will not be moved from the closed position.

A further object is to produce an improved hoisting line tension maintaining device for use with tilting open hearth furnaces.

These and other objects which will be apparent to those skilled in this particular art, I attain by means of the mechanism described in the specification and illustrated in the drawings accompanying and forming part of this application.

In the drawings:

Figure 1 is a more or less diagrammatic side elevational view of a tilting open hearth furnace equipped with a door operating mechanism embodying this invention and which is more or less diagrammatically illustrated in this view;

Fig. 2 is an enlarged view in side elevation of the door operating mechanism disclosed in Fig. 1. This view by dotted lines illustrates the operation of the hoisting line tension maintaining mechanism during tilting of the furnace to pouring and slagging positions.

Fig. 3 is a somewhat diagrammatic perspective view of the door operating mechanism of Figs. 1 and 2;

Fig. 4 is an elevational view looking toward the charging side of a tilting furnace equipped with the door operating mechanism of Figs. 1, 2 and 3. In this view which is also more or less diagrammatic, three only of a series of charging doors are shown, it being understood that such series may include as many doors as desired; and

Fig. 5 is an enlarged sectional view in elevation of the hoisting line tension maintaining mechanism of this invention. In this view, the mechanism, while it embodies the same principle as the mechanism of Figs. 1 to 4 inclusive, has a somewhat different arrangement of the elements of the mechanism.

The open hearth furnace which is more or less diagrammatically disclosed in the drawings is of the tilting type. It has an under frame 5 provided with arcuate rail-like portions 6 (one only being shown), which are supported on anti-friction rollers 7. These rollers are held in spaced relation by an arcuate retainer 8 and are sup-

ported on arcuate tracks 9 (one only being shown) on the top of the base member 10. The furnace is adapted to be tilted about its longitudinal center line 11 by means of suitable power operated tilting mechanism through the agency of a connecting rod 12 as is usual.

Along its front or charging side, the furnace is provided with a number of vertically movable doors 13; there being one door for each charging opening; the number of such openings depending upon the size of the furnace.

Referring to Figs. 2 to 4 inclusive, a hoisting unit 14 is provided for each door and these units are mounted on some suitable support such as member 15 located a sufficient distance above the top of the furnace to provide space for installation of the hoisting line tension maintaining device of this invention.

Each hoisting unit may comprise an electric motor, a reduction gear, a crank or a winding drum, a suitable limit switch and a brake. In Figs. 2 to 4 inclusive, a crank 16 is shown, but it will be understood that a winding drum 42 as disclosed in Fig. 5 may be utilized instead, if desired. The hoisting line may be a steel cable or a chain, or part may be cable and another part chain.

The hoisting line disclosed in Figs. 2 to 4 inclusive, throughout the major part of its length, comprises a steel cable 17 while throughout the remainder of its length a chain 18 is utilized. The cable and chain portions are connected together by means of a turnbuckle device 19 which is used as a connector and as means for adjusting the length of the line as a whole.

At its upper end, the hoisting line is connected to the crank of a hoisting unit as at 20, while at its lower end, as at 21, it is connected to a yoke-like member attached to the furnace door.

The pouring spout 22 of the furnace is located at the side of the furnace opposite doors 13. In order to pour, the furnace is tilted toward the pouring spout side about its longitudinal center line 11 through an arc of about 35°. For the slagging operation, the furnace is tilted in the opposite direction through an arc of about 15°.

During charging, melting down and refining, the furnace is held in its normal horizontal position.

The device of this invention comprises means or mechanism for maintaining a substantially constant tension in the hoisting line during tilting of the furnace to pouring and slagging positions. This device is located above the furnace and engages the hoisting line between the hoisting unit and the furnace door. When the furnace is being tilted to pouring and slagging positions the hoisting unit is not operating and the device of this invention maintains a substantially

constant tension in the hoisting line during tilting of the furnace to such positions.

The tension maintaining device comprises three sheaves which engage the hoisting line at three spaced positions between the hoisting unit and the furnace door. The position of one of these sheaves is fixed. Another of the sheaves is mounted on the top of the furnace and therefore, its position is changed as the furnace is tilted. The third sheave is supported out of line with the other two by a pair of support arms. These support arms are pivotally connected together by means which is coaxial with the shaft of the third, or out of line, sheave. The opposite ends of these support arms are pivotally connected, one adjacent the fixed position sheave and the other adjacent the sheave on the top of the furnace.

Since the hoisting line engages all three of these sheaves and one of the sheaves is held out of line with the other two by the two support arms, a loop is formed in the hoisting line between the fixed position sheave and the sheave mounted on the furnace.

Sheave 23, the fixed position sheave, is mounted for rotation within a support bracket or member 24 attached to the horizontal beam-like member 25 which is carried by vertical supports 26 and 27. Support bracket 24 as shown in Fig. 3 comprises spaced plate-like portions 28 which have aligned holes for receiving shaft 29 of sheave 23.

A sheave 30, which is the second sheave of the tension maintaining device is mounted on a shaft 31 carried by a bracket 32 secured to the top of the furnace at a position which, in this case, is immediately above its longitudinal center line. A sheave 33, the third sheave of the device, is supported out of line with sheaves 23 and 30 by means of support arms 34 and 35. These arms are pivotally connected together by shaft 36, the shaft of sheave 33. Support arm 34 has its end remote from shaft 36 pivotally connected at 34a, to the support member or bracket 24 adjacent sheave 23, while support arm 35 has its end remote from shaft 36 pivotally connected at 35a to bracket 32 within which sheave 30 is journaled.

The hoisting line passes under sheave 23, over sheave 33, and under sheave 30 on its way from the hoisting unit to the furnace door.

A sheave 37 mounted on the furnace directly above the charging door 13 supports the chain portion of the hoisting line which extends vertically downward from the sheave to the furnace door. While bracket 32 for sheave 30 is located directly above the longitudinal center line of the furnace, it may be located at some other suitable position on top of the furnace structure, if desired.

When the hoisting unit is operated to raise and lower the furnace door, which is only while the furnace is in horizontal position, sheave 33 is held in the position shown in Figs. 1 and 2 by support arms 34 and 35.

As the furnace is tilted to pouring and slagging positions, the position of the loop formed in the hoisting line is changed. When moved to pouring position, sheave 33 is moved to the dotted line position 38 and sheave 30 is moved to the dotted line position 39. When the furnace is tilted to the slagging position, sheave 30 is moved to dotted line position 40 and sheave 33 to dotted line position 41.

If the pivot points for the ends of support arms 34 and 35, the ends remote from shaft 36, co-

incided with the axes of rotation of sheaves 23 and 30, the change in the sum of the lengths of the arcs of contact between the hoisting line and sheaves 23, 30 and 33—occurred by tilting of the furnace—would either so increase the tension in the hoisting line as to cause the furnace door to be raised from closed position or would decrease the tension in the hoisting line sufficiently to permit disengagement of the sheaves by the hoisting line.

I have found that it is possible to maintain the tension in the hoisting line substantially constant during tilting of the furnace in both directions, or so nearly constant that the furnace door is not raised from closed position nor is sufficient slack occasioned in the hoisting line to permit disengagement of the sheaves by such line. I accomplish this by locating the pivot point 34a for arm 34 and pivot point 35a for arm 35 at points removed from the axes of rotation of sheaves 23 and 30.

In an installation in which the tension maintaining device of this invention arranged in accordance with the disclosure of Fig. 2 is used in connection with a tilting open hearth furnace of 200 tons capacity, certain of the elements of the device are arranged as follows so far as sizes and locations are concerned.

The distance between pivot point 34a and the center of shaft 36 is 7 feet 7½ inches. Pivot point 34a is located 11 inches to the left of the center of shaft 29 of sheave 23, and is dropped 3¾ inches below the center of such shaft. The distance between the center of shaft 36 and pivot point 35a is 7 feet 4 inches. Pivot point 35a is located 12 and ¾ inches to the left of the center of shaft 31 and is dropped 1 inch below the center of such shaft.

In this installation, the sheaves 23, 30 and 33 are all 15 inches in diameter and are provided with a 2 inch deep hoisting line groove.

The distances between the center of shaft 36 and pivot points 34a and 35a depends upon the available space between the top of the furnace structure and the center of shaft 29 of sheave 23. It is important in laying out the device to make sure that support arms 34 and 35 do not become aligned or in other words, straighten out during tilting of the furnace.

Now referring to Fig. 5, it will be seen that a slightly different arrangement of sheaves and support arms is utilized in the tension maintaining device.

The hoisting unit 42 is here shown of the winding drum type. This unit is mounted on a horizontal platform carried by one of the main rail support beams.

In this form, a chain is used as the hoisting line. Between the hoisting unit and the fixed position sheave 43 over which the chain passes, it passes under guide sheaves 42a and 42b. The shaft of sheave 43 is numbered 44 and is carried by a pair of horizontal channel members 45 (only one being shown) secured to the main rail beams.

Sheave 46, corresponding to sheave 30, is mounted on a shaft 47 carried by bracket secured to the top of the furnace at a point directly above its longitudinal center line 48.

Sheave 49 is the out of line sheave and its shaft is numbered 50. The support elements for this sheave are numbered 51 and 52 and the outer end, in this case the upper end, of support element 51 is pivotally connected to the

channel members 45 at a point below and to the right of shaft 44 of sheave 43.

A sheave 53 mounted on the top of the furnace directly above door 13 keeps the hoisting line (chain) between it and the door vertical when the furnace is in normal or horizontal position, the only position during which the door is operated.

In tilting to the left to pouring position (Fig. 5), sheave 49 moves to dotted line position 49a, while sheave 46 moves to dotted line position 46a. When the furnace is tilted to slagging position, sheave 49 moves to dotted line position 49b while sheave 46 moves to dotted line position 46b. A sheave 53 located above the furnace door side of the furnace holds the furnace door end of the hoisting line in vertical position directly above the door 13.

In an installation in which the tension maintaining device of this invention arranged in accordance with the disclosure of Fig. 5 is used in connection with a tilting open hearth furnace of 175 tons capacity, the pivot point for the upper end of support arm 51 is located 5 inches to the right of the center of shaft 44 of sheave 43, and is dropped 5½ inches below the center of such shaft.

In this installation, the distance between pivot point 53 at the upper end of arm 51 and the center of shaft 50 of sheave 49 is 4 feet 7½ inches while the distance from the center of shaft 50 of sheave 49 to the center of shaft 47 of sheave 46 is 7 feet. In this installation, the pivot point for the lower end of support arm 52 coincides with the center of shaft 47 of sheave 46.

In some arrangements, as in this one, it is only necessary to offset the pivot point of the outer end of but one of the supporting elements for the out of line sheave in order to maintain a substantially constant tension in the hoisting line during tilting of the furnace, or a tension which is so nearly constant that the furnace door is not raised from closed position during tilting nor is sufficient slack occasioned in the hoisting line to permit the line to disengage the sheaves.

From the above it will be apparent that compensation for the changing lengths of the arcs of contact between the hoisting line and the three sheaves comprised in the hoisting line tension maintaining device can be accomplished by properly offsetting, so to speak, the pivot point of the outer end of but one of the supporting elements for the out of line sheave, as in the arrangement of Fig. 5.

The term "sheave" as used herein means any rotatable element capable of holding the hoisting line in place, and the hoisting line contact surface of which is concentric with its axis of revolution.

Having thus described my invention, what I claim as new and desire to secure by Letters Patent is:

1. The combination with a tilting furnace having a vertically movable door on one side and a pouring opening on the opposite side, of a hoisting unit mounted independently of the furnace, a hoisting line operated by such unit and extending therefrom to said door, three spaced hoisting line contact members which are partially encircled by the hoisting line and are arranged at

spaced positions between the hoisting unit and said door, with the intermediate support member out of line with the other two to form a loop in the hoisting line, and means constructed and arranged to support such out of line member and compensate for such changes in the lengths of the arcs of contact between the hoisting line and such members as occur during tilting of the furnace to pouring and slagging positions.

10 2. The combination with a tilting furnace having a vertically movable door on one side and a pouring spout on the opposite side, of a hoisting unit mounted independently of the furnace, a hoisting line operated by such unit and extending therefrom to said door, three sheaves which are partially encircled by the hoisting line and are arranged at spaced positions between the hoisting unit and said door, with the intermediate sheave out of line with the other two to form a loop in the hoisting line, and means constructed and arranged to support such out of line sheave and compensate for such changes in the lengths of the arcs of contact between the hoisting line and said sheaves as occur during tilting of the furnace to pouring and slagging positions.

20 3. The combination with a tilting furnace having a vertically movable door on one side and a pouring opening on the opposite side, or a hoisting unit, a hoisting line extending from such unit to said door, mechanism located between the hoisting unit and said door for maintaining the tension in the hoisting line substantially constant during tilting of the furnace to pouring and slagging positions; such mechanism comprising three sheaves each partially encircled by the hoisting line and so positioned as to form in such line a loop having taut sides, and means for compensating for the changes in the lengths of the sides of such loop as occur during tilting of the furnace to pouring and slagging positions.

30 4. The combination with a tilting furnace having a vertically movable door and an opposed pouring spout, of a hoisting unit mounted independently of the furnace, a hoisting line extending from such unit to said door, and a hoisting line tension maintaining device located between the hoisting unit and said door and employing three spaced sheaves each of which is partially encircled by said line; said device including means for supporting one such sheave out of line with the other two and for compensating for changes in the lengths of the arcs of contact between such line and said sheaves as occur during tilting of the furnace to pouring and slagging positions.

40 5. The combination with a tilting furnace having a vertically movable door on one side and a pouring opening on the opposite side, of a hoisting unit, a sheave mounted on a fixed support above the furnace, a sheave mounted on the furnace, a hoisting line passing under said sheaves and operated by said unit to open and close said door, a third sheave intermediate the other two, out of line therewith and partially encircled by said hoisting line, thus forming a loop in such line, and means for supporting the out of line sheave and compensating for the changing lengths of the arcs of contact between the hoisting line and such sheaves occasioned during tilting of the furnace to pouring and slagging positions.

HARRY L. McFEATERS.
